By Richard B. Owen, Attorney

UNITED STATES PATENT OFFICE.

JOHN L. MAUCH, OF GULF, TEXAS.

COOLING DEVICE FOR CASTING MACHINES.

Application filed June 3, 1922. Serial No. 565,577.

To all whom it may concern:

Be it known that I, JOHN L. MAUCH, a citizen of the United States, residing at Gulf, in the county of Matagorda and State 5 of Texas, have invented certain new and useful Improvements in a Cooling Device for Casting Machines, of which the following is a specification.

The present invention relates to a device 10 for cooling and solidifying layers of liquid hot cast material, such as sulphur, by means of a gas or vapor or mixture thereof and is especially useful in conjunction with a method and apparatus such as is described 15 in my application filed on even date and also in my application filed on May 10, 1921, bearing Serial Number 468,223 now Patent No. 1,417,542.

The object of the invention is to bring a 20 cooling fluid, ordinarily air, into effective contact with the layer of cast hot material such as sulphur, in order to produce quick cooling and economical use of such cooling fluid.

25 A further object of the invention is to provide a device of this nature which will be simple and efficient in construction, reliable in operation, comparatively inexpensive to manufacture and operate, and well adapted 30 to the purpose for which it is designed.

With the above and numerous other objects in view as will appear as the description progresses, the invention resides in certain novel features of construction, and the 35 combination and arrangement of parts as will be hereinafter more fully described and claimed.

In the drawing:—

Figure 1 is a longitudinal vertical section 40 through the device showing the same in combination with an apparatus while in use, and

Figure 2 is a transverse vertical section taken substantially on the line 2—2 of Figure 1 looking in the direction of the arrow.

45 The hot liquid sulphur is discharged upon the wetted belt 1 or upon a layer of previously deposited sulphur 2, forming a comparatively uniform liquid layer by means of the nozzles 3 which may be of any preferred 50 construction and do not form a part of the present invention.

The sulphur will be cooled and solidified due to the cooling action of the surface upon which it is discharged and also due to the 55 cooling action of a stream of air passing

over its upper surface which is supplied by the device about to be described. In order to use such air efficiently it is caused to pass over the deposited sulphur in a comparatively thin stream so that thorough contact 60 may be established between the air and the sulphur, due to their proximity and the air eddies caused by friction.

The device consists of a cover 4 which is suspended over the layer of sulphur in such 65 a manner to obtain clearance of the passage of the air between it and the sulphur. The stream of air is fed into such passage from a header 5 which will receive its supply from the main air duct by means of a flexible connecting duct, not shown, attached to the neck 6. The header may be fully or only partially open over the sulphur layer, but preferably the cover should extend over the header, adjacent to each side of the sulphur layer so 70 as to prevent to a great extent the leakage of air from the header before it has been brought into immediate contact with the sulphur as is shown to advantage in the drawing. This header is also preferably 75 provided with a flexible flap 7 for maintaining contact with a roller 8 adjacent thereto to prevent excessive leakage in that direction, this roller 8 being journaled on a shaft 9 over which extend the hook extensions 10 80 as is indicated by the dotted lines in Figure 1. This roller, by making contact with the surface of the solidified sulphur, will further prevent air leakage in a direction toward the adjacent sulphur discharge nozzle 3. The 85 roller is also necessary to aid in carrying the air header and cover, maintaining a uniform clearance between the same and the surface of the sulphur.

This roller 8 is maintained in its proper 95 position by the guide brackets 11 engaging the shaft extensions from the roller or in any other suitable manner. It is desirable that the roller may rise or lower to maintain contact with the sulphur as the thickness 100 varies. The cover or header are further supported and maintained by bracket extensions 13 which are to be carried by the roller of the adjacent cooling device, or, by a fixed support where there is no adjacent cooling 105 device, as is the case beyond the first nozzle header. One or more such cooling devices may be used, as necessary, to cool the layer or layers being deposited. It will be noted that other fluids than air may be used for the 110

cooling medium, such as humified air, steam at a temperature lower than the solidifying temperature of the substance being cooled, other gas or vapor or mixtures thereof. Such mediums may be artificially cooled before being used if found necessary.

The modification of the invention which I have disclosed with some degree of particularity, refers to the preferred form thereof and has been given only by way of example it being understood that numerous changes may be resorted to within the scope of the invention as hereinafter claimed.

Having thus described my invention what I claim as new is:—

1. A cooling device of the class described including a cover, a header at one end of the cover, a duct for receiving a cooling medium passing through said header.
2. In a cooling device of the class described, a cover, a header at one end of the cover to contain a cooling medium, a flexible flap mounted in the header, a roller contacting with said flexible flap rotatably mounted adjacent the header.
3. In combination, a cover, an air header at one end of said cover, a roller for support-

ing the header, and means for supporting the end of the cover.

4. In combination, a cover, an air header at one end of the cover to contain a cooling medium, a flexible strip in the header, a roller contacting with the flexible strip and supporting the header, a shaft for said roller, guides for engaging the shaft so as to allow the roller to be vertically adjustable, and means for supporting the other end of the cover.

5. In combination, a moving carrier, a roller, a cooling device supported on the roller in spaced relation to the carrier and a layer of solidified material thereon.

6. An apparatus for cooling hot liquid material as it is being cast comprising a moving carrier, a cover, a header at one end of the cover to contain a cooling medium, and means for holding the cover and header in spaced relation above the moving carrier.

In testimony whereof I affix my signature in presence of two witnesses.

JOHN L. MAUCIL.
